UNITED STATES PATENT OFFICE.

HENRY STANLEY, OF ST. JOHNSBURY, VERMONT, ASSIGNOR TO STANLEY & TARBLE.

IMPROVEMENT IN FLOUR AND GRAIN ELEVATORS.

Specification forming part of Letters Patent No. 40,313, dated October 13, 1863.

To all whom it may concern:

Be it known that I, HENRY STANLEY, of St. Johnsbury, in the county of Caledonia and State of Vermont, have invented a new and Improved Mode of Elevating, Conveying, Cooling, and Airing Flour, Meal, Grain, &c.; and I do hereby declare the following to be a full and exact description of the same, reference being had to the accompanying drawings, making part of this specification, in which—

Figure 1 is a perspective view of the interior of a mill, illustrating the application of my invention; and Fig. 2 is an end elevation thereof.

This invention consists, first, in devices for elevating and conveying flour, meal, grain, &c., by the pressure of the atmosphere, which is caused to exert the requisite propelling force by use in connection with a rotary fan, as will be hereinafter explained; second, in an improved reservoir or receiver for cooling and airing said flour, &c.

In order that others skilled in the art to which my invention appertains may be enabled to fully understand and use the same, I will proceed to describe its construction and operation.

In Fig. 1 of the accompanying drawings, A may represent a curb, which covers the mill-stones, and B a pulley upon the lower end of the spindle, upon which the runner-stone is mounted and rotated.

E represents a cylindrical box or casing, in which a rotary fan is adapted to operate.

F is a tube or trough for conveying the flour or meal to the fan-casing E, into which it is deposited through a suitable aperture.

G may represent perforations for supplying air to the interior of the casing E.

H H H is a pipe or tube for conducting the flour from the fan to the receiver or reservoir I I I. Upon this reservoir is erected a frame, J J J J J, over which a covering of gauze or analogous material is secured, for the purpose to be hereinafter explained.

M is a hollow cone suspended directly over the mouth of the pipe H that leads into the receiver I, for the purpose of preventing the flour from being forcibly impelled against the gauze covering of the receiver and cause it to settle down therein.

K is a pipe or tube, through which the flour

flows from the under side of the receiver I to the bolt L.

In Fig 2 is represented a heater or jolter, composed of jointed arms N N N N', the latter of which is pivoted to the floor of the mill and caused to oscillate when the mill is going, so as to operate the striking-arm of the beater by a pin projecting from the pulley S, through which motion is communicated to the bolt L and a spiral spring, attached at one end to the upper end of the vertical arm N and at the other, near the foot of a standard, P, rising from the floor of the mill. The upper horizontal arm, N, works through a corresponding aperture in the standard P.

Motion is communicated from the pulley B to the fan within the casing E by a band, C, working upon a pulley keyed to a short shaft, to which the fan is attached.

O is a vertical shaft provided with a pulley near its upper and lower end, respectively, through the medium of which rotation is imparted to the bolt L by bands Q and R.

Operation: Power being applied to the shaft of the runner-stone, the flour flows through the tube F into the interior of the casing E, whence it is forced up the pipe or tube H by the fan within said casing, and is received into the reservoir I. The air, which the action of the fan condenses, then assumes its original expanded state and passes through the gauze covering of the frame J, while the flour remains in the reservoir I a sufficient length of time to be cooled, aired, and otherwise benefited by the action of the atmosphere, the gauze covering of the frame J admitting a free circulation of air to promote this object. The blast generated by the fan is assisted in the elevation of the flour by the pressure of the atmosphere, consequent upon the partial vacuum created by the successive revolutions of the fan. By the combined action of these two forces the flour, meal, grain, or other article to be treated may be elevated or conveyed to the receiver or other depository with the greatest possible celerity. Each revolution of the pulley S is followed by a stroke from the upper horizontal arm, N, of the beater against the receiver I, which prevents the flour from clogging therein, and causes it to flow regularly into the bolt L.

Having thus described my invention, the following is what I claim as new therein and desire to secure by Letters Patent:

1. The combination of the conducting trough or tube F and tube H with a rotary fan, confined within the casing E and operated substantially as specified, employed to elevate or convey flour or grain to the cooling or airing receptacle.

2. In combination with the aforesaid con-

ducting-tubes F and H, rotary fan, and casing E, the receiver I J M, operated as described, and partially covered with gauze or other porous material, for cooling and airing the article being treated previous to passing into the bolt L.

HENRY STANLEY.
